UNITED STATES PATENT OFFICE.

THOMAS J. DAVIS, OF DUQUESNE, PENNSYLVANIA.

SINTERING APPARATUS.

Application filed May 29, 1923. Serial No. 642,190.

To all whom it may concern:

Be it known that I, THOMAS J. DAVIS, a citizen of the United States, and resident of Duquesne, in the county of Allegheny and State of Pennsylvania, have invented certain new and useful Improvements in Sintering Apparatus, of which the following is a specification.

This invention relates to sintering apparatus and more particularly to sintering apparatus employing a sintering pan adapted to be tilted about a fixed axis to discharge the sintered material, and has for its object the provision of means for trapping and preventing the escape of the dust caused by discharging the sintered material from the pan.

Another object is to provide a sintering apparatus having the novel construction, design and combination of parts described in the following specification and illustrated in the accompanying drawings.

In the drawings—

Figure 1 is a somewhat diagrammatic top plan of a sintering plant constructed in accordance with my invention.

Figure 2 is a side elevation thereof.

Figure 3 is a sectional elevation on the line III—III of Figure 1.

Referring more particularly to the drawings, the sintering plant is shown composed of two buildings, 2 and 3, of ordinary construction, each of which is provided with a charging floor 4.

A plurality of sintering pans 5, of well known construction, such as illustrated and described in the United States patents to Greenawalt, No. 1,098,033, dated May 26, 1914, and No. 1,110,623, dated September

15, 1914, are mounted in a series of openings in the floors 4. The pans 5, as is well known in the art and as described in the Greenawalt patents, are adapted to rotate about a fixed axis into a tilted or inverted position to discharge the sintered material therefrom.

Suitable receiving bins 7 are built below each of the pans 5. The bins 7 are each provided with a screening member 8 adapted to separate the coarse and fine pieces of sintered material, the coarse material flowing over the screen 8 and being discharged from the open lower end of the bin into a car 9 or other conveyance which is positioned alongside the plant, while the fine material passes through the screen and is retained in

the bin, the lower end of which is closed as at 10 up to the screen 8. A hopper 11 is provided adjacent the lower end of each of the bins 7 to permit the discharge of the accumulated fine material.

The bins 7 project through the side wall of the buildings housing the plant, and terminate in a car house 12 which forms a continuation of the main building and is secured thereto. The car houses extend the entire length of the main building and may or may not have their ends closed, as desired.

The charging floor 4 is provided with a track 14, the rails of which are on the opposite sides of the pans 5. The track 14 is adapted to have suitable charging buggies, igniter cars, etc., run thereon, and suitable hoods or covers 16 are also mounted on the track 14 and adapted to be moved over the pans after the sintering operation is completed and prior to discharging the sintered material.

The hoods 16 are adapted to seal with the charging floor and thus prevent the escape of dust from the discharged sintered material upwardly through the building.

The bins 7 and car houses 12 form enclosures to receive the discharged material and, therefore, all the dust created by discharging the sintered material is retained and prevented from scattering over the surrounding country as is now customary.

In order to remove the dust from the bins 7 and car houses 12, I provide an exhaust fan 18 which has its exhaust or inlet port connected to exhaust mains 19 and 20, respectively. The mains 19 and 20 extend along the buildings 2 and 3, respectively, and are provided with numerous branch conduits 21 which have their ends terminating in nozzle portions 22 which enter through the top wall of the car houses 12 and through the bins 7 adjacent the upper end thereof. One of the branch conduits is preferably provided for each of the pans 5 and the nozzle portions 22 are preferably located over the receiving cars 9 and adjacent the upper ends of the bins 7, respectively.

Suitable dust catchers 24 are provided in each of the mains 19 and 20 intermediate the fan 18 and nearest branch conduits 21. The dust catchers 24 may be of any well known form and may be of either the wet or dry class. Preferably the dust catchers will be

of the wet class however, since they will more thoroughly remove the dust and will also dampen the dust collected so that it may be more easily handled when removing it from the catchers.

The dust catchers 24 will remove the dust from the exhausted air before it reaches the fan 18 and prevent it from being discharged through the stack 25 which receives the exhaust from the fan 18.

Suitable dry dust catchers 26 are also provided at intervals along the mains 19 and 20. (See Figure 3.) Preferably one of these dust catchers is provided immediately below each branch conduit 21. The dust catchers 26 may be of any standard design and are adapted to catch the heavier dust particles which settle in the mains as the air is drawn through the branch conduits 20 into the mains.

In operation, after the material in the pan 5 has been completely sintered the hood 16 is moved into position over the pan so as to seal with the floor 4 and the pan is tilted or rotated about its axis in the usual manner to discharge its contents into the bin 7. As the material falls into the bin 7 it will be intercepted by the screen 8 and the coarse and fine particles separated, the coarse particles being discharged into the car 9 while the fines remain in the bin. Heretofore the dumping of the pan has caused great clouds of dust to rise and spread over the surrounding territory to such an extent as to injure all forms of vegetation and also the health of the populace. In the present plant construction, however, the closed bin 7, car house 12 and hood 16 form an effective closure against the spread of the dust, while the exhaust fan 18, mains 19 and 20, branch conduits 21 and accompanying mechanism withdraw the dust from the bin 7 and car house 12 and cause it to be trapped in the dust catchers.

It will, therefore, be apparent that the present invention will effectively overcome the objections to the plants as previously constructed and, therefore, it is a considerable improvement over the art.

I claim—

1. The combination with a sintering apparatus including a pan tilttable about a fixed axis to discharge the sintered material, of an enclosure to receive the material discharged from said pan, and a movable hood adapted to be moved over said pan prior to the tilting thereof.

2. The combination with a sintering apparatus including a pan tilttable about a

fixed axis and to discharge the sintered material, of a fixed charging floor extending around the pan, an enclosure extending downwardly from the floor and adapted to receive the sintered material discharged from said pan, and a movable hood adapted to be moved over said pan and to seal with said floor, said enclosure and said hood being adapted to prevent the escape of dust when the sintered material is discharged.

3. The combination with a sintering apparatus including a pan tilttable about a fixed axis to discharge the sintered material, of a fixed charging floor extending around the pan, an enclosure extending downwardly from the floor and adapted to receive the sintered material discharged from said pan, a movable hood adapted to be moved over said pan and to seal with said floor, said enclosure and said hood being adapted to prevent the escape of dust when the sintered material is discharged, and means for exhausting dust laden air from said enclosure.

4. The combination with a sintering apparatus including a pan tilttable about a fixed axis to discharge the sintered material, of a fixed charging floor extending around the pan, an enclosure extending downwardly from the floor and adapted to receive the sintered material discharged from said pan, a movable hood adapted to be moved over said pan and to seal with said floor, said enclosure and said hood being adapted to prevent the escape of dust when the sintered material is discharged, exhaust conduits communicating with said enclosure, and with a suitable exhaust fan for exhausting the dust laden air from said enclosure, and means for trapping the dust before the air reaches said fan.

5. The combination with a sintering apparatus including a pan tilttable about a fixed axis to discharge the sintered material, of a fixed charging floor extending around the pan, an enclosure extending downwardly from the floor and adapted to receive the sintered material discharged from said pan, a movable hood adapted to be moved over said pan and to seal with said floor, said enclosure and said hood being adapted to prevent the escape of dust when the sintered material is discharged, means within said enclosure for separating the coarse and fine particles of sintered material, and means for exhausting the dust laden air from said enclosure.

In testimony whereof, I have hereunto set my hand.

THOMAS J. DAVIS.
